UNITED STATES PATENT OFFICE

2,638,345

OCCUPANT PROPELLED ROUNDABOUT

Benjamin E. Norvell, Oak Creek, Ariz.

Application August 16, 1947, Serial No. 768,998

6 Claims. (Cl. 272—33)

1

The general object of my invention is to provide a therapeutic and amusement device.

An object of my invention is to provide an amusement and therapeutic roundabout with mechanism and carrying units constructed so that the occupants thereof may cause their lower limbs to contact a surface with varying degrees of contact, and cause rotating motion of the device; the occupants' degree of contact with a surface depending on the adjustments of the device.

Another object of the invention is to provide an amusement and exercising device with mechanism and carrying units so constructed that the occupants thereof may dispose carrying unit elements to contact a surface in controlled and varying degrees, and cause rotating motion of the device; the degree of surface contact depending on the adjustments of the device.

A further object of the invention is to provide an amusement and exercising device with mechanism and carrying units constructed so that the occupants thereof may dispose carrying unit elements to make and break contact with a surface in controlled and varying degrees and cause rotating motion of the device; the occupants' degree of effort in causing carrying unit elements to break contact with the surface, depending on the adjustments of the device.

Another object of the invention, in addition to the heretofore named objects, is to provide a raised construction, so that the carrying units may rise in flight upon contact with said raised construction.

Still another object of the invention, in addition to the heretofore named objects, is to provide a scaled surface so that all measured adjustments may be accurately set.

Other objects will appear as the detailed description is set forth.

In the drawings,

Figure 1 is a perspective view showing carrying-unit contact.

Figure 2 is an enlarged fragmentary side elevational view of the inner portion of the device shown in Figure 1.

Figure 3 is an enlarged fragmentary sectional view of the adjustable mechanism taken on the line 3—3 of Figure 4.

Figure 4 is a plan view of the inner portion.

As shown in the drawing, there is a base 1 having a vertical supporting standard 2 fastened thereto. A horizontal, stationary, circular plate 3 is fastened to the top of the supporting standard 2. A horizontal, rotatable, circular plate 4

2

is located above the stationary circular plate 3. The rotatable circular plate 4 rests on a bearing race 5. A stationary vertical bolt 6 extends upwardly from the top center of the supporting standard 2 and stationary plate 3. The bolt 6 extends through a center hole in the rotatable plate 4. The upper portion of the bolt 6 is threaded and there is a threaded nut 7 screwed thereon. A cotter key 9 passes through a hole in the bolt 6 in order to keep the nut 7 in place. The rotatable plate 4 supports radial arms 8 having scales 10c thereon. The inner ends of the radial arms 8 are swingingly hinged to uprights 13 on the rotatable plate 4 and diametrically opposed adjacent the center hole of rotatable plate 4. Longitudinal slots 10a in the radial arms 8 adjacent the hinged ends thereof extend outwardly. There are corresponding longitudinal slots 10b in the rotatable plate 4. Slidably mounted in the longitudinal slots 10a and 10b between the radial arms 8 and rotatable plate 4 are compression springs 11. A clamping member 12 at the upper portion of the compression spring 11 is for holding the compression spring 11 in place after an adjustment has been made. The compression spring 11 extends downward through the longitudinal slot 10b of the rotatable plate 4. The end 14 of the compression spring 11 underneath rotatable plate 4 is flared to prevent compression spring 11 from coming loose from slidable engagement with longitudinal slot 10b.

In Figure 1, an element of the carrying unit contacts the surface instead of lower limbs of the occupant. Therefore, in Figure 1, element 15 is attached adjacent the ends thereof to a hobby horse 16. Fastened underneath the hobby horse 16 is a vertical fork 17. A wheel 18 having a crank 19 and pedals 20 is rotatably mounted adjacent the lower end of fork 17. Adjacent the neck of the hobby horse 16 is a hand grip 21. There is a convex riser 22 located on a track 23 in the path of the wheel 18 when the hobby horse 16 is occupied.

In order to increase or decrease surface contact of wheel 18 with the track 23 the compression spring 11 is preferably set by an operator before the hobby horse 16 is occupied. Therefore, it can be seen that when compression spring 11 is moved outwardly, the occupant experiences a lighter surface touch of the wheel 18; and when compression spring 11 is moved inwardly, the occupant experiences a heavier surface touch of the wheel 18. It is obvious that the rise in flight when the wheel 18 contacts riser 22 is

increased or decreased in accordance with the setting of the compression spring 11.

An operator may make adjustment of compression spring 11 by lifting radial arm 8 upwardly with one hand and by sliding the compression spring 11 to the position desired with the other hand and then screwing down clamping member 12. When the device is operated by two operators, one could hold up radial arm 8 while the other makes adjustment. Obviously, the units are pulled downward for occupancy.

For semi-helpless paralysis victims, as well as convalescents who have progressed considerably towards recovery, the device shown in Figure 1 is of special benefit for exercise of the lower limbs, either with or without the wheel element contact. Beneficial results may be accomplished when the wheel elements make contact with a surface instead of the occupants' lower limbs. On the other hand, when the wheel elements and attachments have been removed, a doctor, nurse, or attendant may set the compression spring means at a predetermined position along the graduated surface 10c of the radial extending member, so that when the unit is occupied, the occupant's lower limbs touch a surface at one pound, and afterwards, one pound one ounce or two pounds, and so on, until the occupant may walk with little or no assistance. During a portion of this course of procedure, the opposite unit could be occupied by a more vigorous occupant in order to keep the device in motion. In this instance, the compression spring means would be set so that the occupant's lower limbs would make heavier contact with the surface. From the foregoing description, it can be seen that a similar course of procedure may be applied, either with the wheel element contact or occupant contact.

It is obvious from the foregoing description, that occupants could break contact by jumping motion, or that occupants could cause unit elements to break contact with a surface by body movements.

Although I have illustrated specific carrying units, it is obvious that any suitable or conventional carrying units may be used instead of the carrying units I have shown and described.

I have illustrated only two carrying units, but there may be any suitable number of carrying units.

It is obvious that there may be various modifications of my invention, and therefore, I do not limit myself to the exact construction I have set forth.

I claim:

1. A roundabout comprising central supporting means adapted for supporting an assembly for rotation, said assembly comprising a plurality of radially extending members having their inner ends pivotally connected to a central rotatable support, each radially extending member having a propelling member attached to a carrying unit adjacent its outer end, the propelling member having means for being set in motion by the physical effort of the occupant of the carrying unit, each carrying unit suspended over a track because of pressure from compression spring means slidably mounted adjacent the inner end of each radially extending member between the radially extending member and central rotatable support of said assembly so that the degree of contact with said track of said carrying units when occupied may be increased when said compression spring means is moved

inwardly and decreased when moved outwardly.

2. A roundabout comprising central supporting means adapted for supporting an assembly for rotation, said assembly comprising a plurality of radially extending members having their inner ends pivotally connected to a central rotatable support, each radially extending member having a propelling member attached to a carrying unit adjacent its outer end, the propelling member having means for being set in motion by the physical effort of the occupant of the carrying unit, each carrying unit suspended over a track because of pressure from compression spring means slidably mounted adjacent the inner end of each radially extending member between the radially extending member and central rotatable support of said assembly so that the degree of contact with said track of said carrying units when occupied may be increased when said compression spring means is moved inwardly and decreased when moved outwardly, the position where said compression spring means may be set being adjacent a scaled surface, said scaled surface being disposed longitudinally of the radially extending member and adjacent said compression spring means.

3. A roundabout comprising central supporting means adapted for supporting an assembly for rotation, said assembly comprising a plurality of radially extending members having their inner ends pivotally connected to a central rotatable support, each radially extending member having a propelling member attached to a carrying unit adjacent its outer end, the propelling member having means for being set in motion by the physical effort of the occupant of the carrying unit, each carrying unit suspended over a track because of pressure from compression spring means slidably mounted adjacent the inner end of each radially extending member between the radially extending member and central rotatable support of said assembly so that the degree of contact with said track of said carrying units when occupied may be increased when said compression spring means is moved inwardly and decreased when moved outwardly, the position where said compression spring means may be set being adjacent a scaled surface, said scaled surface being disposed longitudinally of the radially extending member and adjacent said compression spring means.

4. A roundabout comprising central supporting means adapted for supporting an assembly for rotation, said assembly comprising a plurality of radially extending members having their inner ends pivotally connected to a central rotatable support, each radially extending member having means adjacent the outer end for substantially supporting an occupant so that the lower limbs of said occupant may contact a surface either with a light or heavy touch because of the action from compression spring means slidably mounted adjacent the inner end of each radially extending member between the radially extending member and central rotatable support of said assembly so that the degree of contact of each occupant with a surface may be decreased when said compression spring means is moved outwardly and increased when moved inwardly, the position where said compression spring means may be set being adjacent scaled surfaces, said scaled surfaces being disposed longitudinally of the radially extending member and adjacent said compression spring means for measuring, gauging and specific adjustment.

5. A roundabout comprising central supporting means adapted for supporting an assembly for rotation, said assembly comprising a plurality of radially extending members having their inner ends pivotally connected to a central rotatable support, each radially extending member having a propelling member attached to a carrying unit adjacent its outer end, the propelling member having means for being set in motion by the physical effort of the occupant of the carrying unit, each carrying unit suspended over a surface because of pressure from compression spring means slidably mounted adjacent the inner end of each radially extending member between said radially extending member and central rotatable support of said assembly, raised construction comprising a plurality of convex risers adapted for contact with said carrying units when said carrying units are occupied so that said carrying units may rise in flight from contact with said surface upon contact with said raised construction after said carrying units have been set in motion.

6. An occupant propelled roundabout comprising central supporting means adapted for supporting an assembly for rotation, said assembly comprising a plurality of radially extending members having their inner ends pivotally connected to a central rotatable support, each radially extending member having means adjacent its outer end for substantially supporting an occupant so that the lower limbs of said occupant may contact a surface either with a light or heavy touch because of assistance from compression spring means slidably mounted adjacent the 35

inner end of each radially extending member between said radially extending member and central rotatable support of said assembly so that the degree of contact of each occupant with a surface may be decreased when said compression spring means is moved outwardly and increased when moved inwardly, the position where said compression spring means may be set being adjacent scaled surfaces, said scaled surfaces being disposed longitudinally of the radially extending member and adjacent said compression spring means for measuring, gauging and specific adjustment.

BENJAMIN E. NORVELL.
